UNITED STATES PATENT OFFICE.

ARTHUR CLEMONT DALE, OF NEW ORLEANS, LOUISIANA.

BOAT.

Application filed December 13, 1921. Serial No. 522,100.

To all whom it may concern:

Be it known that I, ARTHUR C. DALE, a citizen of the United States, and a resident of New Orleans, in the parish of Orleans 5 and State of Louisiana, have invented certain new and useful Improvements in Boats, of which the following is a specification.

This invention relates to boats, and more particularly to an improved propulsion 10 means therefor, together with an improved hull construction designed to insure uniform speed when travelling in a rough or smooth sea, the riding effect being such as to obviate racing propellers, to lessen the 15 draft of the boat as well as to obtain greater speed for the power expended than is possible with other boats, and at a reduced cost and expense of upkeep.

A further object of the invention is to 20 provide a boat structure of simple, durable, and economical form, together with a novel and simple propelling means in the form of an endless device arranged with a series of blades or paddles together with means 25 for driving the same and maintaining the operative blades or paddles at a uniform depth in the water, irrespective of whether the boat is riding in a rough or smooth sea.

Other and further objects of my invention 30 will become readily apparent to persons skilled in the art, from a consideration of the following description taken in conjunction with the accompanying drawings, wherein—

35 Figure 1 is a side elevation of my improved boat and propulsion means therefor.

Figure 2 is a front elevation.

40 Figure 3 is a fragmentary sectional elevation of the endless propeller device and showing one of the paddles or blades, and

Figure 4 is a plan view of the structure shown in Figure 3 completed.

45 Referring to the drawings, in detail, in which like reference characters designate corresponding parts throughout the several views, my improved boat is shown as comprising a duplex hull 10 comprising boat shaped pontoons or hull structures 11 of the usual tapered or pointed bow portions 12 and the stern portions 13. The bottom portions of the hull are provided with spaced keels 14 medially of the members 11 which are joined to complete the hull 10, 50 thus providing an intermediate air space 15 at the bottom designed to lessen the

draft and facilitate keeping the boat upright as well as to permit the same to weather a rough sea and ride the same properly. The bottom portions of the members 11 and the hull 10 are also provided with partitions or floor lines 16 producing air tight compartments or bilges 17 between the same and the bottom portion of the hull to further lessen the draft owing to the 60 65 buoyant action thereof.

The boat may be used as a model for the construction of large sized steamers or small boats, as it is thought will be obvious and within the realm of the invention and the 70 scope of the device to be hereinafter more fully described and claimed. However, as illustrated, the stern of the boat at each hull element is shown equipped with a rudder 18 arranged below the water line 19, being 75 completely submerged to facilitate steering or guidance of the craft. Obviously, any suitable means may be arranged operating the rudders from within the hull so as to swing the same on their pivots or posts 20 80 in a manner well known in the art. At the bow, the same may be covered, as indicated at 21 and a suitable top 22 may be arranged over the open portion of the boat or hull in connection with closed panels of glass or 85 other like material indicated at 23 located at the sides or entirely surrounding the same, including the front or bow and the back or stern portions. The steering wheel 24 having connection with the rudders 18 90 is preferably arranged centrally of the forward portion of the cabin at the bow, as is also a motor 25 which is disposed in the rear thereof so as to balance the boat and make the weight even on either side. 95

The propulsion means which is suitably operatively connected to the motor 25 to be driven thereby consists of a pair of transverse shafts 26 arranged horizontally at the bow and stern and journaled through the 100 sides of the hull so that the ends thereof project. On these projecting ends I have arranged sprocket wheels or toothed disks 27 the teeth of which are designated at 28. An endless propeller is engaged around the 105 aligned pairs of sprocket wheels at opposite sides of the boat or hull and each endless propeller consists of pivotally joined links of equal length, certain of the links, preferably each alternate link 29 being in the form 110 of a curved plate provided with a tooth aperture 30 preferably of rectangular form or

outline to correspond with the shape of the teeth. These apertures are centrally arranged, and at each end the links or plates 29 are provided with means for pivotally connecting the same to links 31 also in the form of plates, as shown. Preferably the links 29 are provided with spaced apertured ears 32 at the ends thereof, designed to receive therebetween the apertured ears 33 located at the ends of the plates 31, the pivotal connection being completed through the medium of headed pintles or pivots 34, the ends of which may be upset for this purpose. In order that the links 31 may cooperate 15 with the teeth 28, they are provided with sockets 35 at the inside, so as to engage or receive the teeth therein, the sockets being centrally positioned equi-distantly from the ends of the links as are the apertures 30, 20 while the links or plates 31 are further provided with laterally projecting paddles 36 which extend at right angles or perpendicularly with respect to the curved plates or links 31 preferably over the sockets 35. The 25 plates 31 are reinforced transversely at the sockets in order to add strength to the paddles or blades and permit the latter to be made of any suitable extension or width, in order to give the proper propelling effect 30 and power.

As will be observed, the alternate links are provided with the paddles or blades 36, in the preferred construction, but it is to be understood that any suitable number of intervening links 29 may be used, according to the power to be derived or generated, as well as the speed to be produced. It will be further seen that the lower lap of the endless drive member at each side is arranged to 35 dip in the water, irrespective of the condition of the water or sea, be it rough or

smooth. This will result in a uniform speed while riding in a rough sea, and will also avoid racing propellers and the usual objections thereto.

In view of the foregoing, it is thought that the operation of the device will be readily understood and in view of the simplicity and practical value, that it will readily commend itself to those skilled in the art.

Having thus fully described my invention, what I claim as new and desire to secure by Letters Patent is:—

1. A boat comprising a duplex hull consisting of a pair of united hulls, the hulls having outer sides and a common vertically extending inner side and also having separate bottoms, each of said bottoms having a keel and a pair of bottom sections flaring upwardly from the keel to the sides of the hull, the adjacent bottom sections of the hulls merging into the common side at a point a substantial distance above the water line to define a substantially closed intervening air space between the hulls, said air space 55 extending the entire length of the hulls.

2. A boat comprising a duplex hull consisting of a pair of united hulls, the hulls having outer sides and a common vertically extending inner side and also having separate bottoms, each of said bottoms having a keel and a pair of bottom sections flaring upwardly from the keel to the sides of the hull, the adjacent bottom sections of the hulls merging into the common side at a 70 point a substantial distance above the water line to define a substantially closed intervening air space between the hulls, said air space 75 extending the entire length of the hulls, propulsion means operating along the 80 outer side of each of said hulls.

ARTHUR CLEMONT DALE.
